[57] CLAIM

The ornamental design for a toothbrush head and handle unit, as shown and described.

DESCRIPTION

FIG. 1 is a top plan view of a toothbrush head and handle unit showing our new design;

FIG. 2 is a side elevational view thereof, the opposite side being a mirror image;

FIG. 3 is a reduced perspective view thereof;

FIG. 4 is a bottom plan view of FIG. 1;

FIG. 5 is a left end elevational view thereof;

FIG. 6 is a right end elevational view thereof; and,

FIG. 7 is a sectional view taken along line 7—7 of FIG. 1.

The broken line showing of the lettering on the handle in FIG. 1 is for illustrative purposes only and forms no part of the claimed design.
